(57) **CLAIM**

I claim the ornamental design for a candy piece, as shown and described.

DESCRIPTION

FIG. 1 is a top, front, right side perspective view of a candy piece;

FIG. 2 is a front elevation view of the candy piece;

FIG. 3 is a rear elevation view of the candy piece;

FIG. 4 is a left side elevation view of the candy piece;

FIG. 5 is a right side elevation view of the candy piece;

FIG. 6 is a top plan view of the candy piece; and,

FIG. 7 is a bottom plan view of the candy piece.

1 Claim, 2 Drawing Sheets

See application file for complete search history.
